PHOTO-PRINTING SYSTEM AND APPARATUS

Matthew H. Loughridge, Bogota, N. J., and Robert Stuart, Forest Hills, N. Y.

Application July 22, 1937, Serial No. 154,974

20 Claims. (Cl. 88—24)

This invention relates to a photo-printing system and the apparatus used in connection therewith and it has for an object to provide a mechanism for automatically photo-printing by time exposures; another object of the invention is to provide a photo-printing and enlarging system; another object of the invention is to provide a printing wheel or drum for printing the subject of a film onto a band of paper in which the mechanism is automatically controlled by the film and by the paper band; another object of the invention is to provide a printing wheel driven by friction from a drive shaft and which can be readily disconnected from the drive; another object of the invention is to provide a rotating printing wheel for a film and a band of paper with a take-up mechanism driven by friction from the printing wheel and another object of the invention resides in the use of a pneumatic controlling system for the take-up of the film and the paper band.

These and other objects of the invention will be more particularly understood from the following specification and the accompanying drawings, in which:

Fig. 1 is a sectional elevation of the printing wheel mechanism taken on line 1—1 of Fig. 3;

Fig. 2 is a side elevation of a printing machine complete corresponding to Fig. 1;

Fig. 3 is a plan view of the machine shown in Fig. 1 with part of the cover removed to show the paper and the film reels;

Fig. 4 is a plan view, partly sectioned, of a portion of the pivoted supporting arm;

Fig. 5 is a plan view of the printing wheel, sectioned on line 5—5 of Fig. 6 and with the cover removed for three sections;

Fig. 6 is a side elevation of the printing drums corresponding to Fig. 5;

Fig. 7 is a detail, partly sectioned, showing the mounting of the drum for the film;

Fig. 8 is a diagram showing the pneumatic control of the system;

Fig. 9 is a front elevation of a tracker board and a portion of the paper band for controlling the operation;

Fig. 10 shows the control of the friction wheel by a diaphragm;

Fig. 11 shows the application of a composite film.

U. S. Patent 2,081,187 issued May 25, 1937, shows a photo-printing system in which the subjects of a motion picture film are transferred and enlarged upon a band of paper. This patent uses a printing wheel in carrying out the

process and provides a time exposure for printing each picture while the film and the paper band are automatically fed to the machine. The present invention relates to a machine of this type and provides for mounting a plurality of 5 these machines on a vertical stand driven by friction from a common drive shaft. Each machine is mounted on a pivoted arm upon which the rotating wheel has its bearings and in operation engages the friction wheel of the drive 10 shaft to operate the machine. The pivoted arm is provided with a spring toggle which normally maintains the friction drive but when the arm is swung out from the engaging position over the toggle this mechanism holds the machine in 15 the inactive position. Any machine may be moved to the inactive position for reloading while the other machines, operated by the same drive, continue in operation.

The machine is provided with a drum for the 20 film at the top with a source of light in the center and with windows, in the drum which register with the frames of the film. If desired, teeth may be provided on the film drum for engaging the apertures of the film. Parallel with 25 the film drum a film reel is provided for feeding the film to the drum and a corresponding take-up reel is provided for taking the film off the drum.

The paper band, as illustrated in the drawings, 30 is arranged for printing an enlargement of the film subjects and is placed around the drum on the printing wheel which is correspondingly larger than the drum used for the film. This drum is also provided with windows and with 35 light chambers so that the optical system projects the subject of each frame of the film upon the paper band and this condition is maintained in fixed relation throughout substantially a revolution of the drum, so that the speed of the 40 drum regulates the length of the time exposure. A reel is provided for feeding the paper band to the drum and a second reel is provided for taking off this paper band after the printing operation.

The take-up reels for the film and for the paper band are driven by a friction drive from the printing wheel with a belt connection to each reel and the usual slip connection in the drive that is provided in take-up devices of this kind. 50 In order that the mechanism may be stopped when the film has ended or in case it breaks, or when the paper band ends or is broken, a mechanism is provided for disengaging this friction wheel under these circumstances and thereby 55

stopping the operation of the take-up mechanism. This control mechanism is operated pneumatically by means of the diaphragm chamber, which controls the bearing support of the friction wheel and when subject to normal air pressure the normal tension of the diaphragm pulls the friction wheel away from its drive and disconnects the drive for the take-up reel. On the other hand, when the diaphragm chamber is 5 vacuumed the external air pressure, acting on the diaphragm, forces the friction wheel into engagement and establishes the drive for the take-up mechanism. A tracker board is provided for the paper band adjacent to the reels. This 10 tracker board is connected with the pneumatic system of the diaphragm chamber and when the paper band moves over this device it seals the connection with the pneumatic system, until the end of the band is reached or until a portion is 15 reached having an aperture provided for control purposes.

When a narrow film is used it may not be practical to use a tracker board having an aperture sealed by the film itself. In this case the tension 20 of the film operating through a lever controls a valve in the pneumatic system which operates to disconnect the friction drive if the film should become broken.

One of the uses for this invention is in connection with an addressing system in which the 25 addresses are photographed on the frames of the film and from these frames they are printed on a band of paper which is afterwards separated by a cutting process and applied to the subject to be addressed. The invention, however, admits of a much wider use than this as it is possible to 30 concentrate a considerable amount of written matter or pictures in the frames of even a small film and then to enlarge these subjects for general 35 use. For instance, picture film may contain the contents of a circular letter including the heading of the letter and the signature but leaving out the address. The circular letter may then be addressed individually by superimposing upon 40 the master film containing the circular letter, a second film containing only the name and the address properly located with reference to the body of the letter. In the application, the addressed film is superimposed upon the master 45 film and both are printed at the same time, making a complete letter by one operation of the machine.

The invention is illustrated in connection with a continuous moving picture film and a continuous band of paper stock upon which an enlargement of the film pictures is printed. It 50 should be understood, however, that the same apparatus and mechanism may be used for printing paper in single sheets and for selectively printing these sheets by applying the system illustrated in 55 application Serial No. 92,271 of July 24, 1936.

It is to be noted that the paper band as used in this invention is the equivalent of a motion picture film and the paper band is used in this 60 connection in this specification and claims.

In general, the construction of the machine corresponds to a turntable around which a row of enlarging cameras have been placed, each with its 65 individual optical system and light chamber, maintained in fixed relation and with means for automatically supplying and taking off the film and the paper band as the turntable rotates.

In the drawings, 11 is the drive shaft driven by the motor 13 through the worm gear 14, Fig. 8, 70 and upon this vertical shaft a friction wheel 12 is

mounted for each printing wheel. The printing wheel 15, Fig. 1, is mounted on the ball bearing 16 on the supporting arm 17 and the ball bearing 18, on the hollow stem 19, and is driven by frictional engagement with the wheel 12. A pair of pipe supports 21 and 22 support the shaft 11 and support the bracket 20 which is hinged at 23 and 24 through the pivot 25 to the arm 17. The stem 26 of the bracket 20 is formed on an inclined plane as indicated in Fig. 4 and engages the plunger 27 on the inclined face which is opposed by spring 28 in the arm 17. In the position shown in Fig. 4, the plunger 27 moves the arm 17 to secure engagement between 15 and 12, thus providing for the operation of the printing wheel. When the 10 arm 17 is moved in the opposite direction until the plunger 27 engages the opposite face of 28, the friction drive 12 is disconnected and the mechanism is inoperative. This enables any one of a number of machines to be taken out of operation 15 while other machines driven by the same shaft may continue in operation.

Upon the wheel 15 the drum 29 is seated as shown and carries at its upper end the film drum 30 which may be mounted by a dowel engagement 25 as indicated at 34, Fig. 7. The source of illumination is indicated by the bulb 44, having its light source at 43 and which projects the light as indicated by the dotted lines through the lens 42, through a window 53, Fig. 7, in the film drum, 30 through the film upon the prism or reflector 33, through the aperture 34, upon the prism or reflector 35 and through the lens 37 and the window or aperture 46 in the paper drum 29 to the surface 41 of the paper band to be printed. In this 35 arrangement it will be observed that the optical system rotates with the wheel 15, the lens 32 being supported by the arm 31, the prism 33 being supported by a ring projecting from 29 and the flange 36 on 29 supporting the prism 35 while the 40 lens 37 is supported by 38 from the wheel 15. It will also be noted from Fig. 5 that the paper drum is radially divided into sections indicated by the lines at 55 and these segments are covered as indicated at 56, leaving a space above the prisms 35 45 for the projected light. This provides a complete and independent projector for each frame of the motion picture film which is rotated by the printing wheel during the exposure.

In the arrangement shown in Fig. 1, where the 50 film 42 leads out horizontally from the film drum, it is necessary to place the prism 33 below the plane of the film so that the prisms may rotate with the printing wheel; for this purpose the light is deflected from 43, through the lens 32, obliquely 55 through the film and upon the reflector 33. The distortion that may be caused by projecting the picture in this way is corrected in the optical system by adjusting the prism 35 and the lens 37 or either of them. This distortion may also be compensated for by inclining the film at an angle to the camera when the film is made and which the oblique projection corrects. It should be understood that the optical system may be varied to 60 suit conditions.

The printing wheel is provided with a stationary cover 48 supported by bars 47 which pass downwardly over the sides of the drum and unite with the supporting arm 17 at 59 and 51. A cover 48 is also provided for the sides and a cover 49 for 70 the top.

Referring to Fig. 8, 56 is a film reel for the film 42 which passes around the film drum 38 and is taken up on the film reel 57 which is provided with a take-up mechanism comprising the 75

belt 62 engaging the belt wheel 63 connected with the reel 61 and the wheel 64 on the stem 65 connected with the friction wheel 66 which engages the printing wheel 15.

6 The paper reel 11 feeds the paper band 41 to the paper drum 39. This paper band is taken off by the reel 78 which has a take-up drive comprising the belt 68, the belt wheel 69 connected with the reel 70 and the belt wheel 67 connected with the stem 65. The take-up mechanism is adjusted to take up the paper under tension throughout the operation. A cover 73 is provided for the paper reels as indicated in Fig. 2 and the cover 12 is provided for the film reels. When two films are to be printed in superimposed relation a film reel 15 may be provided for the film 16 which is fed to the film drum 30 and is taken off on the reel 11. The results illustrated in Fig. 11 may be obtained by 10 this arrangement in which the film a represents the master film, the film b represents the superimposed film and c represents the combined results from a and b. In a the letter 78 is produced and in b the name and address 79 is supplied 15 which at c gives a completely addressed letter as indicated at 80. It should be observed that if this system is to be used for reproducing a circular letter only, then the master film is applied around the film drum 30 and does not require a feeding and a take-up reel. It will be noted from Figs. 1 and 3 that the film reels 60 and 61 are mounted upon the stationary part of the cover which covers the paper drum. This places the film close to the film drum, however, 20 if the film reels are comparatively large, also if the film reels are comparatively large, they may be moved away from the printing wheel. -

The take-up mechanism is controlled by engaging, or disengaging, the friction wheel 66. 25 This wheel, Fig. 10, is mounted on a bearing support 81 which is carried on a sliding arm 82, pivoted to the vertical rod 84 which pivots at 85 and connects by link 86, to rod 87, pivoted at 88 and connecting at 89 to the diaphragm 90 of the diaphragm chamber 91 which is rigidly supported at 30 92 by the arm 11. It will be noted that if air is exhausted from the chamber 91 the friction wheel 66 will be moved to the right due to the action of the atmosphere on the diaphragm 90, this establishes a frictional drive for the shaft 65. On the other hand, if the vacuum in the chamber 91 is destroyed, the diaphragm 90, by its 35 normal bias, moves the wheel 66 to the left and disengages the friction drive. A manual release is also provided for this friction drive, comprising the pin 93 in the arm 82 engaged by cam 94, pivoted in the support 83 and operated by the handle 95, Fig. 8.

The motor 13 operates a suction pump 96 connected by the pipe 97 with the pneumatic system which operates the diaphragm chamber 91. Pipe 97 connects to the tracker board 103 at reel 71 and 104 at reel 70. These tracker boards are constructed as indicated in Fig. 9 with an aperture 104 connected with pipe 97. This aperture is normally sealed by the paper band 41 so that the vacuum in 91 may be maintained. When the end of the paper band is reached, a slot 105 may be provided therein which will operate to stop the take-up mechanism at this point, and of course, if the paper band becomes broken, the seal is thereby destroyed and the friction drive is stopped.

A valve 98 connects with pipe 97 and is controlled by lever 100, pivoted at 101 and biased to

an open position by spring 102. A roller 99 on this lever engages the film 42 where it is maintained taut by the take-up mechanism and the valve is thus maintained closed until the end of the film is reached when it is opened and operates to disengage the friction drive. 5

A peep sight 45 is provided whereby the subject being printed may be viewed on the reflector 35.

The pneumatic control may be applied to other parts of the apparatus, as for instance, to disconnect the friction drive between 12 and 15 and to extinguish the light used for printing but which is not illustrated in the drawings.

Having thus described our invention, we claim: 15

1. A photo-printing apparatus comprising a printing wheel having a drum for the film and for the paper arranged in optical relation for photo-printing, a drive shaft with a continuously rotating drive wheel, a pivoted arm supporting 20 said printing wheel in frictional engagement with said drive wheel and a toggle mechanism controlling said arm for the engagement and disengagement of said driving wheel and printing wheel. 25

2. A photo-printing apparatus comprising a plurality of printing wheels, each having a drum for the film and for the paper arranged in optical relation for photo-printing, a common drive shaft, a drive wheel on said shaft for each printing wheel, a pivoted arm supporting each printing wheel in frictional engagement with its drive wheel and means for independently releasing each printing wheel from its drive wheel. 30

3. A photo-printing apparatus comprising a printing wheel having a small drum for the film and a large drum for the paper arranged on a different plane and in optical relation for photo-printing, means for rotating said drums, an arm pivotally supporting said wheel independently of 40 said rotating means, a film reel and a paper reel supported by said arm independently of said wheel and means for rotating said wheel and for feeding the film and the paper to the drum 45 to be printed.

4. A photo-printing apparatus comprising a printing wheel having a drum for a film and a larger drum for a paper band, a film reel and a paper reel, means for rotating said wheel, means for feeding the film to the film drum and the 50 paper to the paper drum in optical relation for photo-printing, a take-up reel for the film and a take-up reel for the paper, a friction wheel engaging said printing wheel and means connecting said friction wheel with said take up reels 55 for operating the take-up reels.

5. A photo-printing apparatus comprising a printing wheel, a film reel and a paper reel, means for rotating said wheel, means for feeding the film and the paper to the wheel in optical relation for photo-printing, a take-up reel for the film and a take-up reel for the paper, and a friction wheel engaging said printing wheel for operating the take-up reels means controlled by the paper and by the film for disengaging the friction wheel from the printing wheel. 65

6. A photo-printing apparatus comprising a printing wheel, a film reel and a paper reel, means for rotating said wheel, means for feeding the film and the paper to the wheel in optical relation for photo-printing, a take-up reel for the film and a take-up reel for the paper and a friction wheel engaging said printing wheel for op- 70

- erating the take-up reel and pneumatic means controlled by the paper for disengaging the friction wheel from the printing wheel.
7. A photo-printing apparatus comprising a printing wheel, a film reel and a paper reel, means for rotating said wheel, means for feeding the film and the paper to the wheel in optical relation for photo-printing, a take-up reel for the film and a take-up reel for the paper and a friction wheel engaging said printing wheel for operating the take-up reel and pneumatic means controlled by the film for disengaging the friction wheel from the printing wheel.
8. A photo-printing apparatus comprising a printing wheel, a film reel and a paper reel, means for rotating said wheel, means for feeding the film and the paper to the wheel in optical relation for photo-printing, a take-up reel for the film and a take-up reel for the paper and a friction wheel engaging said printing wheel for operating the take-up reel and pneumatic means controlled by the paper and by the film for disengaging the friction wheel from the printing wheel.
9. A photo-printing apparatus comprising a printing wheel, a film reel and a paper reel, friction means for driving said printing wheel, means for feeding the film and the paper to the printing wheel in optical relation for photo-printing, a take-up reel for the film, a take-up reel for the paper, friction means operated by said printing wheel for driving said take-up reels and means for disconnecting the friction drive of the printing wheel and means for disconnecting the friction drive of the take-up reels.
10. A photo-printing apparatus comprising a printing wheel, a film reel and a paper reel, means for rotating said wheel, means for feeding the film and the paper to the wheel in optical relation for photo-printing, a take-up reel, a friction drive operated by said printing wheel for said take-up reel and a diaphragm operated by air pressure controlling the operation of said friction drive.
11. A photo-printing apparatus comprising a printing wheel, a film reel and a paper reel, means for rotating said wheel, means for feeding the film and the paper to the wheel in optical relation for photo-printing, a take-up reel, a friction drive operated by said printing wheel for said take-up reel and a diaphragm chamber connected with said friction drive operating to disconnect the drive when air is admitted to the chamber.
12. A photo-printing apparatus comprising a printing wheel, a film reel and a paper reel, means for feeding the film and the paper separately to different portions of said printing wheel in optical relation for photo-printing from the film to the paper on an enlarged scale, a take-up reel for said film, a take-up reel for said paper, frictionally engaging means for driving said take-up reels, a tracker board for the paper and means whereby said tracker board controls the driving means of said take-up reels.
13. A photo-printing apparatus comprising a printing wheel, a film reel and a paper reel, means for feeding the film and the paper to said printing wheel in optical relation for photo-printing, a take-up reel for said film, a take-up reel for said paper, pneumatic means controlling said take-up reels, a valve controlling said pneumatic means, and means operated by the tension of the film controlling said valve.
14. A photo-printing apparatus comprising a rotating printing wheel having a film drum and a paper drum located in optical relation, a cover for said wheel, a bearing for said wheel and a swinging arm supporting one member of said bearing and rigidly supporting said cover.
15. A photo-printing apparatus comprising a rotating printing wheel having a paper drum with printing apertures, a separate film drum with printing apertures centered on said wheel and means for locking said film drum on said wheel with its printing apertures in register with the printing apertures of said paper drum, a light in the centre of said wheel for printing from the film to the paper and means for feeding the paper and the film as said wheel rotates.
16. A photo-printing system comprising a stand with a vertical drive shaft having a plurality of friction wheels thereon, an arm pivoted on said stand for each friction wheel, a printing wheel rotatably mounted on each arm, said printing wheel having a paper drum and a film drum located in optical relation for printing from the film to the paper, each of said printing wheels being brought into engagement with its corresponding friction wheel when its arm is moved in one direction and disengaged from the friction wheel when the arm is moved in the opposite direction.
17. A photo-printing system as in claim 16, in which the movement of each arm is controlled by a toggle mechanism.
18. A photo-printing apparatus comprising a rotating printing wheel having a film drum and a paper drum located in optical relation for printing from the film to the paper, a cover for said wheel, a take up reel for said film mounted on said cover, a bearing for said wheel and an arm supporting one member of said bearing and rigidly supporting said cover.
19. A photo-printing apparatus comprising a rotating printing wheel having a film drum and a paper drum larger than the film drum located in optical relation for printing from the film to the paper, a cover for said wheel, a take up reel for the film mounted on said cover, a bearing for said wheel, a take up reel for said paper, a supporting arm supporting one member of said bearing, supporting said cover rigidly and supporting said paper take up reel and means operatively connecting said printing wheel with said take up reels.
20. A photo-printing apparatus comprising a rotating printing wheel having a film drum and a paper drum located in optical relation for printing from the film to the paper, a take up reel for the paper and a take up reel for the film, pneumatic means controlling said take up reels, a valve controlling said pneumatic means, a lever controlling said valve, means for holding said film taut and the taut portion of said film engaging said lever to hold said valve closed.
